[57] CLAIM

The ornamental design for an adjustable width doorway safety gate, as shown and described.

DESCRIPTION

FIG. 1 is a front elevational view of an adjustable width doorway safety gate, showing my new design;

FIG. 2 is a top plan view thereof; and

FIG. 3 is a back elevational view thereof.

The broken line showing of doorway frame pillars is for illustrative purposes only and forms no part of the claimed design.

FIG.1

FIG.2

FIG.3
